UNITED STATES PATENT OFFICE.

JAMES W. MYER, OF SAN DIEGO, CALIFORNIA.

PUMP.

No. 839,020.

Specification of Letters Patent.

Patented Dec. 18, 1906.

Application filed August 28, 1905. Serial No. 276,141.

To all whom it may concern:

Be it known that I, JAMES W. MYER, a citizen of the United States, residing at San Diego, in the county of San Diego and State 5 of California, have invented certain new and useful Improvements in Pumps, of which the following is a specification.

My present invention pertains to pumps, and relates more particularly to an improved 10 mechanism for effecting a continuous discharge therefrom.

The invention is illustrated in the accompanying drawings, wherein—

Figure 1 is a front face view of the mechanism; Fig. 2, a side view thereof; Fig. 3, a transverse horizontal sectional view, the main driving-shaft and driving-pinions being shown in full lines; Fig. 4, a side elevation of one of the jacks or lifting-heads as seen from the inner side; Fig. 5, a transverse vertical sectional view thereof; Fig. 6, a horizontal sectional view on the line 6-6 of Fig. 1; and Fig. 7, a detail view of a portion of one of the heads and driving-pinions, the retaining 25 block or section being removed.

The object of my invention is to provide a simple, strong, and effective mechanism for imparting a differential movement to the piston-rods of a double-acting pump, a quick 30 downward movement and a relatively slow upward movement being imparted to the rods, whereby a constant flow of water from the pump is obtained.

The pump proper forms no part of the present invention and any well-known construction may be employed.

The main frame is preferably formed of a single casting comprising a base plate or flange A, surmounted by a substantially U-shaped body B, the forward edges of which are provided with flanges C C, forming ways or guides. Extending upwardly from the body as a continuation of the flanges are two columns D D, which form the support 45 for the main driving-shaft E. A driving-pulley F, preferably a split-wood pulley, is secured to said shaft E by a split flange or hub G. Upon each end of the shaft E is secured a pinion H. A roller I is mounted on 50 the shaft immediately adjacent to each of the pinions, while a similar though somewhat smaller roller J is mounted upon each end of the shaft, being retained thereon by a collar K, pinned to the shaft.

55 A jack or pumping-head is designed to cooperate with each pinion, the jacks being so

positioned that they work in alternation, one moving down as the other is elevated, and vice versa. Inasmuch as the two jacks or heads are the same in construction, a description of one is deemed sufficient herein. Each head comprises a casting having a substantially triangular body with one vertically-disposed side and a relatively long depending arm L. Said head is formed interiorly with a 60 groove or channel M, a track or runway N for the roller J, and a recess O for the reception of the retaining-collar K. By the formation of the channel M an inwardly-projecting flange P is produced upon which roller I bears 65 and runs.

In the form illustrated a centrally-disposed member Q is bolted to the head, a rack R being formed upon said member and extending entirely around the same immediately opposite the channel M. The head is likewise provided with a flange S, which stands in line with flange P and roller I, the latter bearing 70 directly thereon.

As will be seen upon reference to Fig. 5, the flanges P and S prevent the withdrawal of the pinion from the head, and the pinion is held 80 in mesh with the rack R by the rollers I and J. To permit the insertion and withdrawal of the pinion from the head or jack, the flange P 85 is cut away at one side, (see Figs. 4 and 7,) thereby forming a recess T. Normally this recess is closed by a block U, held in place by bolts V, which pass through the block and the casting. 90

The lower end of the arm L on each of the jacks or heads is secured to a slide or frame, which in turn is connected to the piston-rod of the pump. Both of these slides are the same in construction except as to the manner in which they are connected to the piston-rods. This difference will be hereinafter set forth. 95

Extending outwardly from the upper portion of the column D is a lug or ear W. A 100 slide X, preferably of iron or steel, bears against said lug or ear and a roller Y, secured to the column opposite said lug or ear. The slide passes between the roller and the ear, and by reason of the pivotal connection of 105 the lower end of the arm L and the slide being upon the outer side of the latter the upper end of the slide tends normally to bear inwardly against the roller. The pivotal connection between the arm and the slide is 110 effected by a bolt Z, which passes through an opening formed in the lower end of the arm.

The slide at its lower end is formed with a finger A', which passes in rear of the flange C, and acting with a similar finger B', extending around the opposite side of the flange, 5 (see Fig. 6,) serves to hold the slide directly against the forward face of the flange. The slide also carries at its lower end an antifriction-roll C', which bears upon the inner edge of the flange and assists in maintaining the 10 slide in its proper relation, at the same time preventing undue friction between the parts.

The slide X (shown at the right in Figs. 1 and 6) is provided with a bifurcated or U-shaped arm or cross-head D', to which are 15 attached the piston-rods E' F'. The left-hand slide is provided with a single arm or cross-head G', which passes between the bifurcated ends of the arm D' and is connected to a single central piston-rod H'. 20 The slides will therefore pass each other without interference and the double piston-rods, which are connected to one piston or plunger of the pump, be moved up or down in opposition to the movement of the single 25 piston-rod connected to the other plunger of the pump.

In the operation of the pump the pulley-wheel moves in the direction indicated by the arrow in Fig. 2, which will impart to the 30 driving-pinion carried by the shaft E a motion in the direction of the arrow shown in Fig. 4. As the head or jack moves down, carrying with it the cross-arm, to which is attached one of the piston-rods, the pinion will 35 pass along the vertically-disposed side of the rack R. Immediately the pinion passes the upper end of the rack it will begin to lift the head or jack. Inasmuch as the rack is provided with two inclined faces which must 40 travel over the pinion in the act of raising the head or jack, the upward travel of the latter will be slow as compared to its downward movement. Since the jacks work in opposition to each other, one will at all times 45 be moving upwardly, and a constant stream of water is therefore ejected from the pump.

Having thus described my invention, what I claim is—

1. In combination with the piston-rods of 50 a pump, a driving-shaft; a pinion carried by each end of said shaft; and a jack or head for each piston-rod, each of said jacks being connected to one of said rods and provided with a rack which meshes with one of the pinions 55 carried by the driving-shaft, said rack having a substantially vertically disposed portion and two inclined portions, whereby each

jack will be moved down as the pinion works over the vertical portion of the rack.

2. In combination with the piston-rods of 60 a pump; a frame located adjacent thereto; a power-shaft carried by said frame; a pair of ways or guides carried by the frame; a slide mounted upon each of said ways, said slides being connected to the rods; a pair of 65 jacks pivotally connected at their lower ends, one to each slide; a pinion carried by each end of the power-shaft; a rack carried by each jack, with which the pinions mesh, each of said racks having a substantially vertically disposed portion and two inclined portions; and means for preventing the withdrawal of the pinions from the jacks.

3. In combination with the piston-rods of a pump, a frame located adjacent thereto; a power-shaft carried by said frame; a pair of ways or guides carried by the frame; a pair of slides, each extending substantially the length of the ways and connected, respectively, to the rods; means for guiding the 80 upper end of each of said slides; a pair of jacks, one for each slide; pivotal connections between the lower end of each jack and its slide; a rack carried by each jack, said racks being triangular in outline, with one face or 85 stretch in substantial alignment with the piston-rods; and a gear carried by each end of the power-shaft, said gears meshing with the racks, substantially as described.

4. In combination with a piston-rod of a 90 pump, a slide connected to the rod; a jack pivotally connected at its lower end to the slide, said jack being provided with an interiorly-formed channel M, a track or way N, a recess O, and oppositely-disposed ribs or 95 flanges P and S; a rack carried by the jack, said rack standing opposite the channel M; a power-shaft; a pinion carried by said shaft, said pinion being of a diameter greater than the distance between the opposing faces of 100 the flanges P and S; a roller carried by the outer end of the shaft in line with the track or way N; a second roller I carried by the shaft intermediate the flanges P and S; and a removable block secured in a recess or 105 opening formed in the periphery of the flange P.

In testimony whereof I have signed my name to this specification in the presence of two subscribing witnesses.

JAMES W. MYER.
